X-RAY TUBE SIGHTING DEVICE

Thomas Richard Hawks, Washington, D. C.

Application July 29, 1944, Serial No. 547,239

4 Claims. (Cl. 250—64)

(Granted under the act of March 3, 1883, as amended April 30, 1928; 370 O. G. 757)

1

This invention relates to X-ray machines and more specifically to means to facilitate the alignment of the X-ray tube with the film holder and patient.

In one type of X-ray machine the X-ray tube is supported above a table suitable to sustain a patient and for holding a photographic plate or film in a position to photographically record that portion of the patient to be examined. The X-ray tube is customarily mounted for substantially universal movement with respect to the table and heretofore has been brought into alignment with the patient and film holder by trial and error. While this method is fairly satisfactory for experienced operators and when the photograph is to be taken perpendicular to the table; when it is desirable to take a photograph at angles less than right angles with respect to the table it is difficult to align the X-ray tube, patient and film holder. It is an object of the present invention to make the alignment of the X-ray tube, patient and film holder (hereinafter to be referred to as the cassette) accurate, rapid, and simple for even an unskilled operator.

In one aspect invention resides in means associated with the X-ray tube for observing an image of the cassette, a reference mark associated with said means and a sight, the first named means, reference mark and sight being so arranged with respect to each other and the X-ray tube that when the operator sees a given point on the image of the cassette and the sight superposed in the first named means at said reference mark, the axis of the projected rays from the X-ray tube will intersect the cassette at said point. More specifically the means for centering the X-ray tube with respect to a given point on the cassette comprises a mirror for reflecting an image of the cassette for observation, a reference mark on the mirror in the form of hair lines crossing at right angles and a sight of the bead or reticule type so arranged with respect to the X-ray tube that when the image of said given point on the cassette and the sight are observed in the mirror to be superposed at the center of the reference mark the X-ray tube will be in alignment with said given point on the cassette. In one instance the sight is in the form of a transparent plate having crossed hairs formed on its surface the sight being located between the mirror and cassette so that the operator sees images of both the sight, that is the cross hairs, and the cassette in the mirror. However, the sight may be of the bead type and may be located adjacent to the X-ray tube but not

2

between the mirror and cassette. In this instance the operator sees the image of the cassette and the cross hairs on the mirror directly behind the bead sight.

As illustrated herein there are provided two means for aligning the X-ray tube, one of which is mounted in a position to be adjustable with the X-ray tube about the longitudinal axis of rotation of the X-ray tube and the other one of which is mounted in a position to be adjustable with the X-ray tube about the transverse axis of rotation of the X-ray tube. It is inconvenient to have to look first into one means and then into the other while aligning the X-ray tube because of the necessity of moving the head from one position to another.

Accordingly, novelty also resides in constructing one of said means so that it may be adjusted with respect to the X-ray tube for any given distance from the cassette to provide for alignment of the X-ray tube not only about the axis upon which it is mounted for rotation, but also for alignment of the X-ray tube about the axis at right angles thereto. This is accomplished herein by bringing the X-ray tube into alignment with the cassette at a given height by employing both means and then adjusting the angular position of the mirror and sight of one of said means so that at said given height the image of the cassette and sight will be observed to be superposed at the reference mark on the mirror in both transverse and longitudinal directions.

The X-ray tube is customarily housed in a cylinder which has an opening opposite the anode over which is fastened a cone shaped shield through which the X-rays are projected. Novelty also resides in a modified form of the invention which is adapted to be readily attached to the open end of the cone shaped shield. In this form the mirror and sight are supported at the end of the cone shaped shield by a device which automatically centers the mirror with respect to the axis of projection of the X-rays. Still another form of the invention which is especially suitable to be carried around and which in use is placed against the wall of the cone shaped shield comprises a spindle to which is attached a mirror and sight the arrangement being such that a given portion of the wall of the cone shaped shield may be aligned with a given point on the cassette by adjustment of the X-ray tube until the image of the given point on the cassette and the sight are superposed at the reference mark on the mirror. In some X-ray machines, the

shield is cylindrical in shape, hence means is provided for changing the position of the spindle with respect to the wall of such a shield.

The invention will now be described in detail with reference to the accompanying drawings in which:

Fig. 20 is a view of the device partially in section illustrating its use with a cylindrical shaped shield; and

Fig. 21 is a bottom view of the device.

Referring to Fig. 1 the invention is shown as applied to the head 10 of a conventional X-ray machine, the head being mounted for substantially universal adjustment above a table indicated at 12 upon which a patient 14 may be placed for observation and for photographing. The cassette 16, that is the device for holding the film, may be placed beneath the table 12 or above the table beneath the patient and the invention relates to means 18 and 20 mounted on the head for aligning the head and hence the anode of the X-ray tube with a given point generally the center of the cassette so as to insure obtaining a

photograph of the patient which is centrally located with respect to the film.

The head 10 which is also of conventional design comprises a cylindrical housing 22, Figs. 2 and 3, which protects the X-ray tube from damage having a pair of laterally extending conduits 24 through which pass conductors 26 for energizing the X-ray tube. An opening 27 is provided in the lower side of the housing 22 below the anode of the X-ray tube and surrounding this opening is a cylindrical neck portion 28, the lower end of which is provided with a radially extending flange 30. A block 32 provided with a corresponding radially extending flange 34 is fastened to the flange 30 by means of screws. The block 32 has a central aperture 36 which is concentric with the cylindrical neck 28 and is provided on its lower surface with a transverse way 38 having grooves in its opposite walls for slidably receiving a plate 40 having tongues on its opposite edges which cooperate with the aforesaid grooves. The plate 40 is also centrally apertured and has fixed thereto over the aperture a cone shaped shield 42.

By positioning the plate 40 properly in the block 32 the cone shaped shield 42 may be lined up with the aperture in the block 32 and hence aligned axially with the anode of the X-ray tube so that the X-rays projected therefrom pass centrally through the shield 42. The shield 42 is formed of lead and acts as a shield to prevent the scattering of the X-rays which would be dangerous to the operator and the patient. While the shield 42 is illustrated in Fig. 1, as cone shaped it may be cylindrical in shape as illustrated in Fig. 20. The head 10 is mounted for movement transversely of the table 12, between a pair of spaced sleeve like members 46 which in turn are slidably mounted on a pair of horizontal parallel spaced rods 44, Fig. 1, the latter being fixed at one end to a yoke 48. The outer ends of the rods 44 are braced by a pair of converging rods 50 which are attached at one end to the yoke 48 and are connected at their opposite ends to the rods 44 by means of a plate 52. The yoke 48 is pivotally attached to a boss 56 formed on an upstanding column 58 the pivot 54 providing for adjustment of the head about a horizontal axis. By tilting the X-ray tube about the pivot 54 the X-ray tube may be adjusted longitudinally of the table. To provide for tilting movement of the head transversely of the table the block 32 is journalled on the inner ends of a pair of oppositely disposed screws 60, Fig. 3, which are threaded through the spaced members 46. An arm 62 is attached to the block 32. A spindle 64 is attached to the arm 62 and has a screw knob and pointer 66 secured to its outer end which provides convenient means for tilting the head and for simultaneously indicating the degree of tilt.

The means for aligning the X-ray tube with respect to the cassette and patient as shown in the various forms of my invention in general comprises a mirror 68 for reflecting an image of the cassette 16 for observation, the mirror having formed thereon a reference mark 70 which may be a single scratch line or two scratch lines crossed at right angles and a sight 72 located between the mirror and the cassette or at a point adjacent to the mirror but not between it and the cassette, as illustrated in Figs. 11 and 13. The mirror, reference marks, and sight are so arranged with respect to the X-ray tube that when the center of an image of the cassette or some given point thereon as seen in the mirror are

observed to be coincident with the sight at the reference mark the anode of the X-ray tube and hence the axis of the shield 42 will be in alignment with the central portion of the cassette or the observed given point as indicated at 76 in Fig. 1. The reference mark may also take the form of circular scratches as indicated in Fig. 6.

Referring specifically to the preferred form of my invention, and to the sighting means 18 for positioning the X-ray tube longitudinally of the cassette that is lengthwise of the table as seen in Fig. 3a, the device comprises as shown in Figs. 6 to 10, inclusive, a mirror 68 having a reference mark 70 which in this instance is a point formed on the surface of the mirror and a sight 72. The mirror 68, Figs. 6 and 7, is attached to a plate or bracket 82 which is hinged at 84 to a plate 86, the latter having fastened to its rear surface an angle bracket 88 which is adapted to be attached as shown in Fig. 1 to the flange 30 in such a position that the operator may see into the mirror without difficulty. (Fig. 1.) The plate 82 is yieldably held by a spring 90 attached between hooks formed on the plates 82 and 86 against a cam 92 the latter being mounted on a spindle 94 journalled in an inturned ear 96, Fig. 6, the spindle 94 having a knurled knob 98 thereon which provides means for rotating the cam 92 and hence for adjusting the angular position of the plate 82 with respect to the plate 86. The sight 72 in this instance takes the form of a transparent plate 100 which may be of glass or plastic having formed thereon crossed scratch lines 102 and concentric circles 104. The plate 100 is inserted in a grooved block 106 and is fastened thereon by rivets the block 106 being arranged to be moved toward and away from the mirror 68. To this end the block 106 is provided with a rearwardly extending arm 108 which projects through a slot 110 formed in the plate 82. A pin 112, Fig. 8, is journalled in the rearwardly extended arm 108 with its opposite ends extending beyond the sides of the arm and is adapted to receive leaf springs 114, Fig. 10, which bear against the rear surface of the plate 82 and hence yieldably hold the block 106 against the plate 82 and yet permit adjustment of the block along the slot 110. The adjustment of mirror 68 angularly with respect to the plate 86 and of the sight 100 with respect to the mirror 68 permits the operator to set the device so that the X-ray tube will be aligned not only longitudinally of the table but also transversely of the table at any given height of the X-ray tube from the surface of the table. The manner in which this is accomplished will be described hereinafter.

A somewhat simpler device for aligning the X-ray tube is indicated in Figs. 11 and 12. In this instance, a mirror 68 is employed as in the previous case the mirror being, however, attached directly to the flange 30. The mirror has the usual reference mark 70 but in place of the sight 72 used in the previous construction a wire 116 having a bead sight 118 is employed. In this case, the bead sight 118 is not positioned between the mirror and the cassette. As will be seen by reference to Fig. 11, the sight is mounted adjacent to the mirror and between the operator and mirror. The bead sight 118 is adjustably fastened to the mirror by passing the upper end of the wire 116 through the shank of a screw 120 the screw in turn being passed through a bracket 122 and secured in place by a nut 124. By turning the nut the wire may be jammed between the bracket and head of the screw so as to clamp it

in a given position. As will be observed the bracket 122 is fastened to the upper edge of the mirror. In Fig. 12 there is shown beside the usual reference mark 70 additional reference marks 126. The reference marks are designated 25, 30 and 40 and so positioned that when the bead 118 is lined up with a given reference mark the X-ray tube will be angularly positioned with relation to the cassette to insure correct alignment of the X-ray tube transversely of the cassette for the distance it is away from the cassette as indicated by the numeral opposite the reference line.

The means described above provide for longitudinal adjustment of the X-ray tube and may be adjusted to align the X-ray tube transversely of the tube so that the X-ray tube may be brought into proper alignment both transversely and longitudinally for a given height with a single device. The means 20 is provided for initially obtaining correct alignment of the X-ray tube transversely whereupon the means 18 may be set by adjustment of its mirror and sight to bring them into such relation that when the image of the cassette and the sight are seen to be superposed in the mirror at the center of the reference mark the X-ray tube will be aligned transversely of the cassette. The means 20 shown in Figs. 4 and 5 comprises a mirror 68 having a reference mark 70 thereon attached by welding or soldering to the inner surface of a cylindrical housing 128 having a bracket or collar 130 thereon by means of which it may be attached to one end of the housing 22 as indicated in Figs. 2 and 3. The housing 128 is so positioned that the surface of the mirror is at an angle of 45° with the axis of the shield 42, Fig. 1. Beneath the mirror and mounted on the flange 30 is placed the sight 72, which in this instance, as shown particularly in Fig. 3, comprises a flat strip like member 132 placed on edge in a horizontal position parallel to the reference mark 70. The position of the mirror 68, reference mark 70 and sight 72 are such that when the operator observes an image of the cassette and the sight superposed in the mirror at the reference mark the axis of the shield 42 and hence the anode of the X-ray tube will be in transverse alignment with the center of the cassette.

While thus far the sighting means has been described solely with reference to the alignment of the X-ray tube with the cassette it is evident that it also provides a ready means for aligning the patient with respect to the cassette and X-ray tube. Referring to Fig. 1, for example, if the operator 74 looks into the mirror 68 and sees the point 76 of the cassette and sight 72 in superposed position at the reference mark 70, he is in fact looking along a line of sight so positioned that a given point on any object placed on the table will be aligned with respect to the X-ray tube and cassette, if the aforesaid given point on the object lies in the line of sight. It is evident therefore that the operator may look into the mirror and align the patient so as to bring a particular portion of the body into alignment with the X-ray tube and cassette for photographing by shifting or orienting the patient until the particular spot desired for photographing is brought into the aforesaid line of sight.

It may be desirable in certain instances to provide sighting means which is not necessarily permanently attached to the X-ray apparatus and hence there is provided as shown in Figs. 13 to 16, inclusive, a detachable holder 136 arranged to be mounted at the open end of the shield 42 for sup-

one bar 144 on the end of the support 136. In this case the mirror 68 is supported so that the reference mark 70 lies on the axis of the shield and consequently no adjustment of the device is necessary for changes in the distance of the X-ray tube from the cassette. The support 136 comprises a pair of plates 138 provided with lugs 140 which are adapted to be slidably received in slots 142 formed in an elongated bar 144. The plates are held on the bar 144 by straps 145 and are yieldably urged toward each other by a pair of springs 146 disposed between the straps 145. The plates are interconnected by links 148 to an arm 150 which is pivotally attached at 151 to the bar 144. Each plate 138 is provided near its outer edge with a pair of spaced pins having necked ends 154 which are adapted to engage the rolled over edge 156 at the open end of the shield 42. The aforesaid construction is such that when the holder 136 is placed against the lower edge of the shield by pushing the plates 138 apart sufficiently to allow engagement of the necked end portions 154 of the pins with the turned edge 156 and the plates are released, the holder will automatically center itself with respect to the axis of the shield. A second set of pins 158 are provided at the inner edges of the plates 138 to take care of shields of smaller diameter. The mirror 70 is mounted at the center of the bar 144 at an angle of approximately 45° with the plane of the mouth of the shield and a sight 72 is mounted at one end of the bar 144 in such a position with respect to the reference mark 70 on the mirror that when the image of the cassette and sight 72 are seen superposed in the mirror at the reference mark the axis of the shield will be in alignment with the center of the cassette.

The form of the invention just described is somewhat bulky and cannot be conveniently carried around and hence a pocket device is shown herein which may be used on any existing equipment. This modification of the invention is shown in Figs. 17 to 21, inclusive, and comprises the usual mirror 68, reference mark 70 and sight 72. The mirror 68 is fastened to a block 158 the block in turn being secured to a spindle 160 which as shown in Fig. 18 may be held by the operator against the inner surface of the shield 42. The angle at which the mirror is positioned is such that when the image of a given point on the cassette, preferably near its perimeter and the sight are observed to be superposed at the reference mark 70 that peripheral portion of the shield against which the spindle 160 is held will lie in line with that given point on the cassette. The X-ray tube may be aligned with the cassette with only one setting of this device, however, it is desirable to establish several points in order to insure alignment of the X-ray tube with the cassette. This may be done by the operator holding the device against the wall of the cone at any point in its circumference, as indicated in Figs. 17 and 19. The upper edge of the block 158, as indicated at 159, is at right angles to the longitudinal axis of the spindle 160 and hence the device may be held in the correct position by bringing the upper edge 159 into engagement with the rolled over edge of the shield 42. The shield, frequently referred to as the cone, is not always conical. It may be cylindrical as illustrated in Fig. 20 and to make the device adaptable to both forms of the shield a collar 166 is slidably mounted on the spindle 160 so that the angle of the spindle 160 with respect to the surface of the shield may be varied. A series of annular notches

170 are formed in the spindle for the reception of a spring pressed detent 168 for locking the collar in a given position. In order that the collar may be disposed of without removing it from the spindle 160 in instances where the device is to be used with a cone shaped shield a recess 122 is formed in the upper surface of the block 158 of such depth as to receive the collar in an out of the way position as shown in Fig. 18.

In using the sighting means illustrated in Figs. 1 to 12, the operator places the cassette on or below the table 12 as may be desired and then looking into the mirror 68 adjusts the position of the X-ray tube by longitudinal movement about the pivot 54 until he observes in the device 10 the center or some other given point on the cassette and sight to be superposed at the reference mark on the mirror. This takes care of the longitudinal adjustment of the X-ray tube. He then adjusts the X-ray tube about the axis of the pins 60 until he observes in the device 20, the center of the cassette and sight to be superposed at the reference mark in the mirror. This takes care of the transverse adjustment of the X-ray tube. Then he goes back to the device 18 (of Fig. 6 or Fig. 11) and adjusts the position of the mirror and sight until the image of the center of the cassette and sight are observed to register both transversely and longitudinally with the reference mark. Thereafter, for that given distance of the X-ray tube from the cassette, both longitudinal and transverse adjustment of the X-ray tube may be obtained solely by use of the device 18 (of Fig. 6 or Fig. 11). If the distance is changed between the X-ray tube and cassette the mirror and sight of the means 18 must be reset for the transverse alignment by the means 20 as outlined above.

In using the device shown in Figs. 13 to 16, inclusive, the support 136 is placed over the end of the shield 42 and the X-ray tube is then adjusted in both transverse and longitudinal directions to bring the center of the cassette and sight at the center of the mirror as indicated by the cross-reference marks 70.

When the device shown in Figs. 17 to 20 is employed, it is placed with its spindle 160 against the wall of the shield and with the edge 159 in engagement with the rolled over edge of the shield. The operator then looks into the mirror and brings a given point on the cassette in line with the sight and reference mark which thereby brings that portion of the cassette within the cone of the projected rays from the X-ray tube. When the line of sight has been established by any of the means described, the patient may then be placed on the table and moved about until the part that is to be photographed lies along the line of sight whereupon that part of the patient will be in the correct position to be photographed.

The invention described herein may be manufactured and used by or for the Government of the United States of America for governmental purposes without the payment of any royalties thereon or therefor.

Having fully described my invention, I claim:

1. In an X-ray machine in which the X-ray tube is adjustable about transverse and longitudinal axes with respect to a cassette, means to facilitate alignment of the X-ray tube transversely and longitudinally of the cassette with respect to a given point thereon, said means comprising a mirror mounted for rotation about the transverse axis of rotation of the X-ray tube, said mirror having a reference mark parallel to the transverse

axis of rotation, a mirror mounted for rotation about the longitudinal axis of rotation of the X-ray tube, said second mirror having a reference mark thereon parallel to said longitudinal axis of rotation, sights cooperating with said mirrors in such a manner that when the images of the said given point on the cassette and sights are observed to be superposed on the reference marks the X-ray tube will be aligned both transversely and longitudinally with respect to said given point and means for adjusting the angular position of one of the mirrors with respect to the X-ray tube so that at a given distance the image of said point on the cassette will be seen to be superposed with its sight both transversely and longitudinally in said one mirror.

2. In an X-ray machine in which the X-ray tube is adjustable about transverse and longitudinal axes with respect to a cassette, means to facilitate alignment of the X-ray tube transversely and longitudinally of the cassette with respect to a given point thereon, said means comprising a mirror mounted for rotation about the transverse axis of rotation of the X-ray tube, said mirror having a reference mark parallel to the transverse axis of rotation, a mirror mounted for rotation about the longitudinal axis of rotation of the X-ray tube, said second mirror having a reference mark thereon parallel to said longitudinal axis of rotation, sights cooperating with said mirrors in such a manner that when the images of the said given point on the cassette and sights are observed to be superposed at the reference marks the X-ray tube will be aligned both transversely and longitudinally with respect to said given point, and a bracket for pivotally supporting one of said mirrors with respect to the X-ray tube and means for tilting said bracket to cause an image of said point on the cassette and sight to be superposed at the reference mark in both longitudinal and transverse directions in said one mirror.

3. In an X-ray machine in which the X-ray tube is adjustable about transverse and longitudinal axes with respect to a cassette, means to facilitate alignment of the X-ray tube transversely and longitudinally of the cassette with respect to a given point thereon, said means comprising a mirror mounted for rotation about the transverse axis of rotation of the X-ray tube, said mirror having a reference mark parallel to the transverse axis of rotation, a mirror mounted for rotation about the longitudinal axis of rotation of the X-ray tube, said second mirror having a reference

mark thereon parallel to said longitudinal axis of rotation, sights cooperating with said mirrors in such a manner that when the images of the said given point on the cassette and sights are observed to be superposed at the reference mark the X-ray tube will be aligned both transversely and longitudinally with respect to said given point, a bracket for tiltably supporting one of said mirrors with respect to the X-ray tube and a cam for tilting the bracket to cause the image of said point on the cassette and sight to be superposed at the reference mark in both transverse and longitudinal directions on said mirror.

4. In an X-ray machine in which the X-ray tube is adjustable about transverse and longitudinal axes with respect to a cassette, means to facilitate alignment of the X-ray tube transversely and longitudinally of the cassette with respect to a given point thereon, said means comprising a mirror mounted for rotation about the transverse axis of rotation of the X-ray tube, said mirror having a reference mark parallel to the transverse axis of rotation, a mirror mounted for rotation about the longitudinal axis of rotation of the X-ray tube, said second mirror having a reference mark thereon parallel to said longitudinal axis of rotation, sights cooperating with said mirrors in such a manner that when the images of the said given point on the cassette and sights are observed to be superposed at the reference marks the X-ray tube will be aligned both transversely and longitudinally with respect to said given point, and a bracket for tiltably supporting one of the mirrors with respect to the X-ray tube, a cam for tilting the bracket to cause the image on said point on the cassette and sight to be superposed at the reference mark on both transverse and longitudinal directions in said mirror, and means for adjusting the position of the sight with respect to the mirror.

THOMAS RICHARD HAWKS.
